UNITED STATES PATENT OFFICE

KARL LITZELBERGER, OF HOLLIS, NEW YORK

PERMUTATION LOCK

Application filed February 8, 1928. Serial No. 252,849.

This invention relates to a permutation lock for use in connection with the locking bolt structures of safe and vault doors, and has for its object to provide, in a manner as hereinafter set forth, a permutation lock of the push-pin type so constructed and arranged whereby the surreptitious operation thereof to release the bolt structure, with which it is associated, is reduced to a minimum.

A further object of the invention is to provide, in a manner as hereinafter set forth, a permutation lock of the push-pin type including a locking bolt structure shifting means, a permutable locking mechanism for said means, and a locking device for said mechanism, and with said mechanism and device including means for controlling alarm circuits to indicate when the lock is being opened by an authorized person and when an attempt is made to open the lock surreptitiously.

A further object of the invention is to provide, in a manner as hereinafter set forth, a permutation lock of the push-pin type including concealed means for releasing the locking bolt structure shifting means when the permutable locking mechanism becomes damaged or impaired.

Further objects of the invention are to provide, in a manner as hereinafter set forth, a permutation lock of the push-pin type which is comparatively simple in its construction and arrangement, strong, durable, compact, thoroughly efficient in its use, conveniently operated to released position, readily installed, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference

characters denote corresponding parts throughout the several views:

Figure 1 is a side elevation of a permutation lock in accordance with this invention.

Figure 2 is a longitudinal sectional view thereof.

Figure 3 is a longitudinal sectional view of the permutable mechanism in locking position.

Figure 4 is a side elevation of the permutable locking mechanism in released position.

Figure 5 is a section on line 5—5 Figure 1.

Figure 6 is a section on line 6—6 Figure 1 and further illustrating in dotted lines a pair of locking bolt structures in locked position.

Figure 7 is a front elevation of the lock.

Figure 8 is a rear elevation thereof.

Figure 9 is a section on line 9—9 Figure 1.

Figure 10 is a section on line 10—10 Figure 1.

Figure 11 is a detail in longitudinal section of the locking device for the permutable locking mechanism.

Figure 12 is a section on line 12—12 Figure 1.

Figure 13 is a section on line 13—13 Figure 11.

Figure 14 is a fragmentary view in elevation of the permutable locking mechanism.

Figure 15 is a section on line 15—15 Figure 3.

Figure 16 is a section on line 16—16 Figure 3.

Figure 17 is a section on line 17—17 Figure 3.

Figure 18 is a section on line 18—18 Figure 3.

Figure 19 is a section on line 19—19 Figure 3.

A permutation lock, in accordance with this invention, comprises a front plate referred to generally at 1 and formed of an outer and an inner portion 2, 3 respectively and with the former of greater diameter than the latter. The edge of the portion 2 is beveled as at 4. The plate 1 is formed with an axial opening 5, an opening 6 arranged below, in alignment with and of smaller diameter than the opening 5, and a pair of spaced openings 7 arranged above the open-

ing 5 and with each opening 7 positioned at one side of the opening 5. The plate 1 has projecting from its front face a collar 8 having its inner face forming a continuation of the opening 6. See Figure 2. The outer diameter of the collar 8 gradually decreases from its inner toward its outer end. With reference to Figure 7 the outer face of the plate 1 above each opening 7 is formed with a scale or a series of graduations arranged in arcuate form as indicated at 9. Forwardly of the front of the plate 1, at the vertical median thereof and projecting outwardly therefrom is a support 10 for a depending pointer 11 for a purpose to be presently referred to.

Arranged rearwardly of the plate 1, as well as being fixedly secured thereto and arranged in spaced relation therewith is a casting referred to generally at 12. Holdfast devices 13' and spacing collars 14' are provided for fixedly securing the casting 12 to the plate 1 and further for maintaining said casting spaced rearwardly from the plate 1. With reference to Figure 2 the casting 12 includes a cylindrical body portion 13 provided at its forward end with a flange 14 and at its rear end with a flange 15. The flanges 14 and 15 are of annular contour. The upper portion 30 of the flange 14 is thickened as at 16 and the upper portion of the flange 15 thickened as at 17. The lower part of the flange 14 is provided with an opening 18 and a rearwardly extending collar 19 which registers 35 with the opening 18. The lower part of the flange 15 is thickened as at 20 and provided with an opening 21 opposing the opening 18 and collar 19 but of a diameter less than the diameter of said opening 18 and collar 19. The openings 18 and 21 are positioned in 40 alignment with respect to the longitudinal median of the body portion 13. The thickened parts 16, 17 of the flanges 14, 15 are formed with openings 22, 23 respectively 45 which are arranged in alignment and further disposed in alignment with respect to the longitudinal median of the body portion 13. With reference to Figure 5 the flange 14 is formed with a pair of openings 24 which are 50 arranged in alignment with the openings 7 formed in the front plate 1. With reference to Figure 6 the flange 15 is provided with a pair of openings 25 which are arranged in alignment with the openings 24. Formed integral with the lower portion of the flange 15 and extending rearwardly therefrom is an arm 26 which terminates in an upstanding circular member 27 constituting a combined support and bearing provided at its lower portion with a pair of spaced openings 28.

Formed integral with the lower part of the forward face of the member 27 is a pair of spaced, opposed forwardly directed hollow

protuberances 29, each* registering with an opening 28. The protuberances 29 are also integral with the arm 26. See Figures 1 and 2. Integral with the member 27 and extending rearwardly therefrom is a pair of collars 30, each registering with an opening 28. The protuberances 29 and collars 30 in connection with the member 27 provide bearings for a purpose to be presently referred to. Integral with the upper portion of the member 27 and projecting forwardly therefrom is a pair of spaced sleeves 31, constituting bearings and each of which registers with an opening 32 formed in the member 27. The member 27 centrally thereof is provided with an opening 33 of greater diameter than the openings 28 and 32. With reference to Figure 2 the body portion 13 is open at its forward end and has secured against its inner face at its rear end a circular plate 34 of appropriate thickness and which is formed with a centrally arranged opening 35 disposed in alignment with respect to the opening 33. The plate 34, see Figures 2 and 3 is provided with a pair of diametrically opposed openings 36, 37, one arranged at the top and the other at the bottom of the plate. The forward face of the plate 34 is recessed as at 38 to provide a pocket and said openings 36 and 37 communicate with said recess. 95

The locking device for the permutable locking mechanism includes a pair of releasable locking elements of like construction, and the description of one will apply to the other. The locking elements are arranged to be shifted in opposite directions relatively to each other when it is desired to release the permutable locking mechanism. The locking elements further constitute supports or pivots for certain elements of the locking bolt structure shifting means. The locking elements are also of the permutable type and are best shown in Figures 1, 2, 5, 11 and 13. Each locking element includes a lengthwise shiftable rock shaft 39 provided at its outer end with a sleeve 40 carrying a handle 41. See Figure 11. The shaft 39 is formed with a key-way 42, carrying a key 43 for slidably connecting therewith a peripherally grooved collar 44, provided with an extended hub 45 mounted on the shaft 39. See Figure 11. The sleeve 40 extends through an opening 7 and projects from the front plate 1 and is arranged below and in proximity to a scale 9. The shaft 39 extends through an opening 24, an opening 25 and through an opening 32 and projects from member 27. The plate 34, see Figure 2, has its rear face flush with the rear end of body portion 13. The sleeve 42 is mounted in a sleeve 31 and extends into the member 27. See Figure 2. The collar 44 abuts against the forward end of the sleeve 31. See Figure 2. The shaft 39 intermediate its ends is formed with a laterally extending stud 46 which coacts, in a manner to be pres- 130

ently referred to, with a flanged sleeve 47 provided with a bayonet-shaped slot 48. The sleeve 47 is loosely mounted on the shaft 39 and its flange is indicated at 49. Extended from the flange 49 is a locking lug 50 for a purpose to be presently referred to. The body portion 13 of the casting 12 is formed with lateral extensions 51 each associated with a shaft 39. Each extension 51 has an opening 52. See Figure 11, and which is aligned with an opening 25. Mounted on the shaft 39 is a flanged sleeve 53 which extends through the aligning openings 25 and 52 and said sleeve 53 has its flange 54 at the forward end thereof and said flange 54 is interposed between the flange 49 and an extension 51. The flange 54 is provided with a notch 55 through which is adapted to extend the lug 50 to lock the sleeve 53 from revolving about the shaft 39. The lug 50 is also adapted to extend into a socket 56 formed in the extension 51 and aligning with the notch or groove 55 in the flange 54. Fixedly secured to the shaft 39 forwardly of the lug 46 is a flanged collar 57. The flange of the collar is indicated at 58. Loosely mounted on the shaft 39 is a collar 59 and interposed therebetween and the collar 57 is a coiled controlling spring 60 for said shaft 39. The sleeve 53 is formed with a peripheral key 61 for a purpose to be presently referred to. See Figure 11. Mounted in aligning collars 29, 30 and extending through an opening 28 is a rock shaft 62. See Figures 1 and 2. The shaft 62 projects forwardly from the collar 29 and rearwardly of the collar 30. The forward end of the shaft 62 carries a crank arm 63 provided at its upper end with a cam 64. The crank arm 63 at its upper end extends into the grooved collar 44 and the cam 64 rides against the periphery of said collar whereby when the shaft 39 is rocked in one direction the crank arm 63 will be shifted outwardly, under such conditions rocking the shaft 62 in a direction to move a latching member 65 from latching position with respect to the permutable locking mechanism. The latching arms are oppositely disposed with respect to each other, see Figure 8, and engage in a peripherally grooved projection 66 formed at the rear of the permutable locking mechanism. See Figures 1 and 8. The latching arms 65 prevent the longitudinal shifting of the permutable locking mechanism so that the latter cannot be actuated to released position with respect to the locking bolt structure shifting means until said latching arms 65 are moved clear of the projection 66.

The locking device for said permutable locking mechanism further acts as an additional locking means for the locking bolt structure shifting means as the lugs 50 normally prevent the shifting of the sleeves 53 to which certain elements of the locking bolt structure shifting means are keyed and this

function will be hereinafter more fully referred to.

The lugs 46 coact with the collars 47 for the purpose of maintaining the shafts 39 extended against the action of the controlling springs 60. The shafts 39 are automatically shifted inwardly, by the springs 60, when the lugs 46 are positioned to enter the slots 48 of the collars 47. The collars 47 are adjustable on the shafts 39 so that the turning movement of the shafts 39 will be to a greater or less extent depending upon the position of the slots 48 relative to the shafts 39. When the lock is closed the handle members 41 are in a vertical position and the lugs 46 ride against the free edge of the collars 47 and which prevents the inward shifting of the shafts 39. It will necessitate the shafts 39 to be turned to position the lugs 46 to oppose the slots 48 to enable the springs 60 to shift the shafts 39 inwardly whereby the lugs 46 will pass into the slots 48. After the lugs 46 have passed into the slots 48, the shafts 39 are again turned in the same direction so that the lugs 46 will abut against one side wall of the slots 48 and the shafts 39 will be arrested from further turning with respect to the collars 47. After the lugs have been positioned in the manner as stated the shafts 39 are pulled outwardly and on the outward movement thereof the collars 47 are carried therewith whereby the lugs 50 will be moved clear of the flanges 54 of the sleeves 53, under such conditions releasing certain of the elements of the bolt structure shifting means to permit of such means being operated in the manner as hereinafter referred to. The scales or graduations 9 assist the operator to properly position the shafts 39 to arrange the lugs 46 opposite the slots 48, as the lugs are set with respect to the scales. The operator will know to what extent the handles 41 are to be shifted with respect to the scales or graduations 9 to properly position the shafts 39 to enable the subsequent releasing of the lugs 50 from the flanges 54 of the sleeves 53.

The permutable locking mechanism for the locking bolt structure shifting means is best shown in Figures 2, 3 and 4, and is normally held from actuation to prevent the shifting therefrom from locking position with respect to said means by the locking device heretofore referred to. After the permutable locking mechanism has been released from the locking device, it can be adjusted to release the locking bolt structure shifting means whereby the latter can be rocked for the purpose of shifting the bolt structure from active or locking position with respect to the door of the safe or vault.

The permutable locking mechanism includes a rotatable and longitudinally shiftable shaft 67 having its inner end formed with the grooved projection 66. The groove 133

in the projection 66 is indicated at 68. The outer end of the shaft 67 is provided with a head 69 formed with a serrated finger or handle portion 70. Fixed to the shaft 67 and overlapping the rear portion of the head 69 is an annulus or collar 71 having its outer edge provided with a dial 72. The outer edge of the annulus 71 is beveled. See Figures 3 and 4. Loosely mounted on the shaft 67, is a sleeve 73 having its outer end formed with an annular flange 74 which abuts the annulus 71. The inner end of the sleeve 73 is peripherally threaded as at 75. Mounted on the sleeve 73 and bodily carried therewith is a sleeve 76 having its outer end provided with an annular flange 77 recessed in its outer face, as at 78 for the reception of the flange 74. A part of the outer edge of the flange 77, is beveled as at 79 and provided with a dial 80. The outer edge of the annulus 71 is flush with the beveled edge portion 79 of the flange 77. The flange 74 is concealed by the annulus 71 and the flange 77. The pointer 11 is associated with the dials 72 and 80. A disc is indicated at 81 and which is interposed between the flange 77 and the front plate 1 and said disc 81 has a centrally arranged opening 82 through which extends the sleeve 73. Integral with the disc 81 and extending rearwardly therefrom is a sleeve 83 which surrounds the sleeve 76. The disc 81 and sleeve 83 have a snug fit with sleeve 76 so as to be carried therewith when sleeve 76 is revolved, but disc 81 and sleeve 83 can be revolved relative to sleeve 76 and which will be hereinafter referred to. The element 10 extends forwardly from disc 81. A handle 84 is on element 10 to retain disc 81 and pointer 11 stationary when adjusting sleeve 76. Sleeve 83 extends through opening 5 and has mounted on its rear end a ring 85 provided with spaced protuberances 86 for a purpose to be hereinafter referred to.

The ring 85 is bodily carried with the disc 81 when the latter is revolved about the sleeve 76. The sleeve 73 is of greater length than the sleeve 76 and projects from the rear end of the latter. That end of the sleeve 73 which projects from the inner end of the sleeve 76 is provided with the threads 75. Threadedly engaging with the threads 75 is an interiorly threaded collar 87, which in connection with the flange 74 couples the sleeve 76 to sleeves 73. The collar is provided with sockets 86' to receive a suitable instrument for securing it in position. Arranged within the forward end of the body portion 13, see Figure 2, is a flanged bearing 87, in the form of an annulus, and through which extends the sleeve 76. The bearing 87 is stationary and has its flange 88 abut against the forward end of the body portion 13. The sleeve 83 is arranged forwardly of the bearing 87. See Figure 3. The sleeve 76 has its rear end peripherally threaded as at 88' and threadedly engaging with

said threads 88' is a collar 89 which projects rearwardly from sleeves 73 and 76. The collar 89 is locked to the sleeve 76 by a retaining screw 90. The rear edge of the collar 89 is provided with a cylindrical protuberance 91 see Figures 3 and 4. The protuberance 91 provides means for connecting or coupling a plunger device, to be presently referred to, with the sleeve 76 so that said plunger device will be revolved with the sleeve 76 upon the shaft 67.

The plunger device, best shown in Figures 3, 4, 15 and 16 comprises a collar 92 formed with a pair of spaced, opposed annular flanges 93, 94. The flange 93 is of less thickness than the flange 94 and is provided with an opening 95 for the reception of the protuberance 91. See Figure 3. The flange 93 is arranged forwardly with respect to the flange 94 and the latter is provided with a pair of oppositely disposed, spaced arcuate slots 96, 97. See Figure 16. Extending rearwardly from the collar 92 is a hub 98, upon which is mounted a circular apertured disc 99 which abuts against the collar 92 and is retained in abutting position by a securing collar 100 positioned on the hub 98. The collar 92 is adjustable relatively to the disc 99, through the medium of the slots 96, 97 and the holdfast devices 101, 102. See Figures 3, 16. Each of said holdfast devices consists of a short bolt countersunk in and extending through the disc 99 and also extending through a slot 96 or 97 and carrying on its threaded end a nut which is positioned between the flanges 93, 94. See Figure 3. The collar 92 is mounted on the shaft 67. Fixedly secured to the disc 99 and projecting rearwardly therefrom is a pair of plunger members 103, 104. The disc 99 at its rear end is provided with a bayonet-shaped slot 105. See dotted line showing in Figure 4. Coacting with the slot 105 is a stud 106 carried by the shaft 67 and the latter is employed for coupling the plunger device to the shaft 67 whereby said device will be bodily carried with the shaft 67 when the latter is rotated or turned.

Mounted on the shaft 67, rearwardly of the plunger device, and operated from the latter is a locking device for the bolt structure shifting means. Said locking device is capable of bodily rotating with the shaft 67, and is further arranged relative to the shaft 67 whereby the latter can be shifted lengthwise independently of said locking device, and the latter comprises a barrel 107 formed of two different inner diameters. The portion of greatest inner diameter is indicated at 108 and the portion of smallest inner diameter is indicated at 109, and the latter is seated upon the shaft 67. The portion of greatest inner diameter is spaced from the shaft 67. The forward end of the barrel 107 is of reduced outer diameter as indicated at 110. The forming of the barrel of two inner diam-

eters provides a shoulder 111. See Figure 3. The reduced forward portion 110, of the barrel 107 is provided with a slot or notch 112 for the reception of the stud 106 whereby the locking device can be coupled with the shaft 67 so as to bodily rotate therewith. Extending into and threadedly engaging with the rear end of the barrel 107 is a peripherally threaded, flanged collar 112' which 5 seats on the shaft 67. The flange of the collar 112' is indicated at 113 and is countersunk in a setting head 114 which is mounted upon the rear end of the barrel 107. The flange 113 is secured to the setting head 114 10 by a plurality of holdfast devices 115. See Figure 3. The outer edge of the setting head 114 has a portion thereof beveled and which is provided with a dial 116. See Figure 8. The setting head 114 is arranged forwardly 15 with respect to the groove 68 formed in the extension 66. The latching arms 65 are arranged rearwardly of the setting head 114 and the latter is positioned against the rear face of the member 27. See Figures 3 and 4. 20 Secured to the shaft 67 and arranged within the barrel 107 is a collar 117 arranged against the inner end of the collar 112. Positioned against the collar 117 and mounted on the shaft 67 is a washer 118. Arranged within 25 the barrel 107 and interposed between the washer 118 and shoulder 111 is a coiled controlling spring 119 for the shaft 67 and which normally tends to maintain said shaft 67 in the position as shown in Figure 3. 30 Slidably mounted on the barrel 107 is an apertured throw-out disc 120 carrying a plurality of forwardly extending abutment fingers 121 which are engaged by the plunger members 103, 104 for the purpose of shifting the disc 120 rearwardly on the barrel 107 35 to the position as shown in Figure 4 for a purpose to be presently referred to. The abutment fingers 121 extend into the openings 36, 37. See Figure 3. The said fingers also 40 extend into the recess or pocket 38 and are arranged rearwardly of a controlling disc 122 provided with openings 123 for the passage of the plunger members 103, 104. The disc 122 is formed with a series of openings 123, see 45 Figure 5. The disc 122 is adjustable so that selective openings therein can be positioned to cooperate with the plunger members 103, 104, for the passage of said members to engage the abutment fingers 121 for the purpose of shifting the throw-out disc rearwardly 50 on the barrel 107.

The barrel 107, in proximity to its forward end, is provided with a laterally extending annular flange 124. See Figures 3, 4 and 5. 55 The said flange 124 is provided with a pair of outwardly disposed arcuate slots 125, through which extend holdfast devices 126 for engagement with the disc 122 whereby the latter will be secured in set position relative to the barrel 107. The disc 122 is revolu-

lubly adjusted on barrel 107, is arranged forwardly of flange 124 and is retained on the reduced forward end 110 of barrel 107 by a retaining collar 127. The plate 34, having the openings 36, 37 and recess 38 is stationary 60 and through the openings of said plate 34 extends the barrel 107. The throw out disc 120 is provided with two sets of locking members 128, each set positioned at the lower portion of a side of the disc at the edge thereof. The locking members 128 project forwardly from and are adapted to extend into the bolt structure shifting means for the purpose of locking said means. The locking members 128 are arranged exteriorly of the 65 barrel 107 at each side thereof.

Interposed between the plunger device and the locking device and surrounding the shaft 67 is a coiled spring 129 for normally maintaining the plunger device a substantial distance forwardly of the locking device. The strength of the spring 129 is materially less than the spring 119 which acts as a means for normally returning the shaft 67 to its normal position as shown in Figure 3. 70

The throw-out disc 120 is also spring controlled and for such purpose a controlling spring 130 is employed which is mounted on the barrel 107 and interposed between a pair of collars 131 and 132. The collar 131 abuts 75 against a boss 133 formed on the forward face of the member 27. See Figure 3. The collar 132 normally abuts against the disc 120 and it is formed with a peripheral groove 134 for a purpose to be presently referred to. 80 The collar 132 is secured to the disc 120 and it is capable of being shifted rearwardly, in a manner as hereinafter referred to by the concealed means for the purpose of releasing the bolt structure shifting means when the 85 permutable locking mechanism becomes damaged or is impaired.

The locking bolt structure shifting means comprises a rock shaft 135, a tubular shaft 136 mounted on the shaft 135, a handle member 137 secured to the outer end of the shaft 136 and a handle member 138 at the outer end of the shaft 135. The shaft 136 is of less length than the length of the shaft 135 and revolves on the latter. The shaft 136 extends 90 through the opening 6 and abuts against the outer end of the collar 8. See Figure 2. The shaft 135 extends through the shaft 136, projects from the rear end thereof and also extends through the opening 21. See Figure 2. 95 The outer end of the shaft 135 has a head 139 which in connection with a cap nut 140 secured to the rear end of the shaft 135 couples the latter to the plate 1 and also to the casting 12. The shaft 136 in proximity to 100 its rear end is provided with a flange 141 which abuts against an eccentric 142 secured to the rear end of said shaft 136. Fixed to the shaft 135 and opposing the eccentric 142 is an eccentric 143. Secured to the shaft 136 105

is a collar 144 which in connection with the head 145 formed on the outer end of the shaft 136 prevents lengthwise shifting of the latter. The head 145 abuts against the collar 144. See Figure 2. Extending laterally from the eccentric 142 is a crank arm 146 and extending from the eccentric 143 is a crank arm 147. The crank arms are oppositely disposed with respect to each other. Pivotedly connected at its lower end, to the outer end of the crank arm 146, as at 148 is an upstanding arcuate link 149 which is keyed at its upper end by a key 61 to a sleeve 53 on a shaft 39. See Figure 11. Pivotedly connected at its lower end, to the outer end of the crank arm 147, as at 150 is an upstanding arcuate link 151 which is keyed at its upper end to the other sleeve 53 carried by the other shaft 39. The links 149 and 151 are oppositely disposed with respect to each other and each is provided with an opening 152 for connection with a locking bolt structure conventionally shown in dotted lines in Figure 6. The link 149 is formed with a set of openings 153 and the link 151 with a set of openings 154. The said sets of openings are adapted to receive the sets of locking members 128 carried by the throw-out disc 120 and when said locking members 128 are seated in the sets of openings 154 the links 149 and 151 are locked from movement. The arrangement of the eccentrics, in connection with the crank arms provides for the shifting of the links 149, 151 in opposite directions with respect to each other for the purpose of moving the locking bolt structure to and from locking position with respect to the door of a safe or a vault.

The flange 15 is apertured as at 155' and formed with tubular extensions 156' forming continuations of the openings 155' and which provide guides for certain of the locking members. The thickened part 17 of the flange 15 is formed with openings 157 to provide guides for other of the locking members. See Figure 1. The means which provide the guides for the locking members are arranged on opposite sides of the flange 15. The links 149, 151 are positioned between the thickened part 17 of the flange 15 and the extensions 51. See Figure 1.

The links are simultaneously operated and the action is had when the operator grips the handles 137, 138 and shifts them in opposite directions relatively to each other. The shafts 135, 136 cannot be rotated until the locking members 128 are shifted clear of the links 149, 151.

For the purpose of releasing the locking members 128, from the links 149, 151, in case that the permutable locking mechanism becomes damaged or is impaired, a shifting mechanism is provided for moving the throw-out disc 120, rearwardly on the barrel 107, independently of the plunger members 103 and

104. Said means comprises a longitudinally disposed bar 155 which is slidably mounted in the portions 16, 17 of the flanges 14, 15 respectively. The forward end of the bar 155 will normally seat in a socket formed in the rear face of the reduced portion 3 of the front plate 1. The socket is indicated at 156. To have access to the rod 155 for the purpose of shifting it, it will necessitate boring through the front plate 1 under such conditions such shifting mechanism is concealed. The rear end of the rod 155 has connected therewith a depending fork 157 which engages in the grooved collar 132. The bar 155 bodily shifts with the throw-out disc 120 when the latter is moved rearwardly on the barrel 107 and the plunger device engages with the abutment fingers 121 for the purpose of shifting the locking members rearwardly. Now if the plunger device becomes impaired in any manner, the bar 155 can be shifted rearwardly, after one has access to the front end of the bar 155 by boring through the plate 1. The bar 155 is shifted rearwardly which carries the fork therewith, and the latter seating in the collar 132 will move it rearwardly and as the collar 132 is connected to the throw-out disc 120, the latter will also be carried rearwardly and the locking members will be shifted clear of the links 149, 151 under such conditions the shifting means for the locking bolt structure can be operated.

The lock includes three controlling means for alarm circuits. One of the controlling means is for the purpose of sounding an alarm when one starts to open the lock, irrespective if the person opening the lock is authorized or not. Another of the controlling devices provides means for sounding an alarm when an attempt is made to open the lock surreptitiously and another of the controlling devices is to indicate that the party who is opening the lock is authorized to do so. The casting 12 includes an extension 158 provided with binding posts 159 which lead to circuit connections. The extension 158 carries a series of contacts 160, 161 and 162. Associated with the contact 160 is a controlling element 163. Associated with the contact 161 is a controlling element 164 and associated with the contact 162 is a controlling element 165. Each of said controlling elements is in the form of a lever. The controlling elements 164 and 165 are pivotally supported upon the extension 158 and the controlling element 163 is pivotally connected upon a lug 166 formed on the casting 12.

The controlling element 164 is employed to provide for the sounding of an alarm when one attempts to operate the shaft 39 irrespective if the one that attempts the operation is authorized or not. When the shafts 39 are adjusted so that the lugs 46 will enter the slots 48 and the shafts 39 swung inwardly the flange 58 will engage the controlling mem-

ber 164 and shift it from its engagement from the contact 161 and thereby provide for the sounding of the alarm. The electrical arrangement is such that when element 164 clears contact 161 the alarm will be sounded. The controlling element 163 is operated from the lugs 86 whereby when the plate 81 is revolved, or when the plate 81 is bodily revolved with the sleeve 76 the lugs 86 will shift the element 163 for the purpose of closing the circuit to the contact 160 thereby sounding an alarm to indicate that the lock is being surreptitiously tampered with. The controlling element 165 is operated from a plunger 167 and engaged by the corrugated edge of the controlling disc 122 and the vertical movement of the plunger 167 will provide for the sounding of an alarm to indicate that the lock is being opened by one authorized to do so. The corrugated or notched edge of the controlling disc 122 is indicated at 168. See Figure 14. The plunger 167 is also shown in Figure 14 and on the reciprocation of the plunger 167 the controlling element 165 will be intermittently rocked on its pivot whereby the alarm will be intermittently sounded. The disc 122 is revolved by the shaft 67, when the lug or protuberance 106 engages in the notched part 112 and the turning of the shaft 30 is had for the purpose of positioning the openings 123 in selective arrangement for the passage of the plunger members 103, 104 to engage the abutment fingers 121 for the purpose of shifting the throw-out disc 120 rearwardly to release the bolt structure shifting mechanism.

After the permutable locking mechanism has been released, the sleeve 76 is adjusted to its desired extent, and which can be ascertained from the dial 80 as the operator is familiar with the setting. The desired extent for the adjusting of the lug 91 is to have the same enter the opening 95 so that the collar 92 will be coupled with the sleeves 45 73 and 76 to rotate therewith or rather revolve therewith. After the collar 92 has been coupled to the shaft 67, the latter is pulled out and adjusted until the protuberance 106 enters the slot 105. The shaft 67 is then 50 turned slightly and the plunger device is coupled therewith. The plunger members are now in position to pass through the controlling disc 122 to engage the abutment fingers 121. When the shaft 67 is pulled 55 outwardly, it is done against the action of its controlling spring 119, and after the plunger device has been coupled to the shaft 67, said shaft is released and the action of the spring will carry the plunger device rearwardly, so that the plunger members 103, 104 will extend through the controlling disc 122, engage the abutment fingers 121 and shift the throw-out disc rearwardly, which in turn 60 will carry the locking members clear of the links 149, 151, and under such conditions the

bolt shifting means can be actuated for the purpose of releasing the bolt structure from locking engagement with respect to a door.

The controlling disc 122 is set to arrange certain of the openings to oppose the abutment fingers by the setting head 114. After the disc 122 has been adjusted it is fixed in its adjusted position. The shaft 67 is rotated to turn the disc to an extent to position the selected openings 123 for the passage of the plunger member. The operator governs the extent of turn from the dial 72 as he is familiar with the setting position of the disc.

In Figure 6 there is shown conventionally and in dotted lines a pair of oppositely disposed locking bolt structures 167, 168 for engagement respectively in opposite sides 169, 170 of the wall of the door opening. Guides 171 are provided for structures 167, 168 and associated with these latter are combined projecting and retracting devices 172, 173 respectively. The device 172 is coupled with link 149 for operation thereby and device 173 is connected with link 151 for actuation thereby. This showing is made by way of example, as any suitable locking bolt structures capable of being actuated by the links 149, 151 may be employed.

What I claim is:—

1. A permutation lock comprising a locking bolt shifting means, a permutable locking mechanism therefor and including a slidable and rotatable spring controlled plunger device and a slidable, spring controlled locking device, said locking device engaging in said shifting means to lock it and moved to released position by said plunger device, and a permutable locking means common to said mechanism and shifting means for normally retaining them from movement.

2. A permutation lock comprising a locking bolt shifting means including a pair of oppositely movable swinging links for projecting and retracting the bolt in opposite directions, a permutable locking mechanism for said links and including a slidable and rotatable, spring controlled plunger device and a slidable, spring controlled locking device normally engaging in said links to prevent the swinging movement thereof, said locking device being moved to released position with respect to said links by said plunger device, and a locking means common to said mechanism and shifting means for normally retaining them from movement.

3. A permutation lock comprising a locking bolt shifting means, a permutable locking mechanism therefor including a plunger device and a locking device, the latter engaging in said shifting means for locking it and the former for moving the locking device to released position with respect to said shifting means, a locking means common to said mechanism and bolt shifting means for normally retaining them from movement, and a

concealed releasing means for said locking device operated independently of said mechanism and said locking means and supported by said mechanism.

4. A permutation lock comprising a locking bolt shifting means, a permutable locking mechanism therefor including a plunger and a locking device, the latter normally engaging in said shifting means for locking it and moved to released position by said plunger device, a permutable dual locking means common to said mechanism and bolt shifting means for normally retaining said mechanism and bolt shifting means from movement, and a releasing means for said locking device operated independently of said mechanism and dual locking means when normally in inactive positions.

5. A permutation lock comprising a locking bolt shifting means including a pair of oppositely movable swinging links operated from a common shaft therefor and providing for projecting and retracting oppositely disposed bolts, a permutable locking mechanism for said links, and a locking means common to said mechanism and bolt shifting means for normally retaining them from movement, said links pivotally supported from said locking means.

6. A permutation lock comprising a locking bolt shifting means including a pair of oppositely movable swinging links operated from a common shaft for projecting and retracting oppositely disposed bolts, a permutable locking mechanism for said links, and a dual locking means common to said mechanism and said shifting means for normally retaining them from movement, said links pivotally supported from said dual locking means.

7. A permutation lock comprising a locking bolt shifting means including a pair of oppositely movable swinging links operated from a common shaft therefor and providing for projecting and retracting oppositely disposed bolts, a permutable locking mechanism for said links, a locking means common to said mechanism and bolt shifting means for normally retaining them from movement, said links pivotally supported from said locking means, and a concealed releasing means coacting with certain elements of said mechanism for releasing said shifting means independently of the operation of said mechanism.

8. A permutation lock comprising a locking bolt shifting means including a pair of oppositely movable swinging links operated from a common shaft for projecting and retracting oppositely disposed bolts, a permutable locking mechanism for said links, a dual locking means common to said mechanism and said shifting means for normally retaining them from movement, said links pivotally supported from said dual locking

means, and a concealed releasing means coacting with certain elements of said mechanism for releasing said shifting means independently of the operation of said mechanism.

9. A permutation lock comprising a locking bolt shifting means, a permutation locking mechanism therefor and including a rotatable, slid able plunger device and a spring controlled locking device, said locking device engaging in said shifting means for locking the latter and said plunger shifting said locking device to release said shifting means, and a permutable locking means common to said mechanism and said shifting means for normally retaining them from movement.

10. A permutation lock comprising a locking bolt shifting means, a permutation locking mechanism therefor and including a rotatable, slid able plunger device and a spring controlled locking device, said locking device engaging in said shifting means for locking the latter and said plunger shifting said locking device to release said shifting means, and a permutable locking means common to said mechanism and said shifting means for normally retaining them from movement, said locking mechanism further including means to provide for said plunger device engaging with said locking device at selective points.

11. A permutation lock comprising a locking bolt shifting means, a permutable locking mechanism therefor including a plunger device and a locking device, the latter engaging in said shifting means for locking it and the former for moving the locking device to released position with respect to said shifting means, a locking means common to said mechanism and bolt shifting means for normally retaining them from movement, and a concealed releasing means for said locking device operated independently of said mechanism and said locking means and supported by said mechanism, said mechanism including means to provide for the plunger device engaging with said locking device at selective points.

12. A permutation lock comprising a locking bolt shifting means, a permutable locking mechanism therefor and including a shiftable and rotatable spring controlled plunger device and a slid able, spring controlled locking device, said locking device engaging in said shifting means to lock it and moved to released position by said plunger device, and a permutable locking means common to said mechanism and shifting means for normally retaining them from movement, said mechanism including adjustable means to provide for the plunger device engaging with said locking device at selected points.

13. A permutation lock comprising a locking bolt shifting means including a pair of oppositely movable swinging links for pro-

jecting and retracting the bolt in opposite directions, a permutable locking mechanism for said links and including a slidable and rotatable, spring controlled plunger device and a slidable, spring controlled locking device normally engaging in said links to prevent the swinging movement thereof, said locking device being moved to released position with respect to said links by said plunger device, and a locking means common to said mechanism and shifting means for normally retaining them from movement, said mechanism including adjustable means to provide for the plunger device engaging with said locking device at selected points.

15 In testimony whereof I affix my signature hereto.

KARL LITZELBERGER.
